UNITED STATES PATENT OFFICE

MAURICE SHEPHERD, OF PARTINGTON, ENGLAND

DESIGN FOR A PLAYING CARD

Application filed May 14, 1930, Serial No. 35,649, and in Great Britain January 21, 1930. Term of patent 7 years.

To all whom it may concern:

Be it known that I, MAURICE SHEPHERD, a British subject, residing at Partington, county of Lancaster, England, have invented a new, original, and ornamental Design for Playing Cards, of which the following is a specification, reference being had to the accompanying drawing, forming part thereof.

The figure is a plan view of the back of a playing card showing my new design.

I claim:-

The ornamental design for a playing card as shown and described.

In testimony whereof I have hereunto set my hand.

MAURICE SHEPHERD.
